UNITED STATES PATENT OFFICE

106,288

DESIGN FOR A SHOE

Walter Ebling, Rochester, N. Y., assignor to E. P.
Reed & Co., Rochester, N. Y., a corporation of
New York

Application September 7, 1937, Serial No. 71,497

Term of patent 3½ years

To all whom it may concern:

Be it known that I, Walter Ebling, a citizen of the United States of America, residing at Rochester, in the county of Monroe and State of New York, have invented a new, original, and ornamental Design for a Shoe, of which the following is a specification, reference being had to the accompanying drawing, forming a part thereof.

In the drawing:

Fig. 1 is a side elevation of a shoe showing my new design, and

Fig. 2 is a plan view of the same.

I claim:

The ornamental design for a shoe, as shown.

WALTER EBLING.
